UNITED STATES PATENT OFFICE.

JACOB S. THORN, OF PHILADELPHIA, PENNSYLVANIA.

DESIGN FOR A SHINGLE OR ROOFING-PLATE.

SPECIFICATION forming part of Design No. 18,209, dated March 27, 1888.

Application filed May 7, 1887. Serial No. 237,487. Term of patent 14 years.

To all whom it may concern:

Be it known that I, JACOB S. THORN, a citizen of the United States, residing at Philadelphia, in the county of Philadelphia and State of Pennsylvania, have invented and produced a new and original Design for Metallic Roofing-Plates or Shingles, of which the following is a specification, reference being had to the accompanying drawings, forming part thereof.

10 Figure 1 is a perspective view of my newly-designed roofing-plate, and Fig. 2 a side view of the same, these two views being deemed necessary to fully illustrate my design.

My new design consists of a roofing-plate having a thickened lower edge, side edges parallel to its median line, and an elongated projection extending along the median line on its upper surface.

15 A is the face or upper visible part of the shingle, having side edges, *a a*, parallel to its median line.

20 B is the raised or struck-up lower edge of the shingle, extending below the parallel sides *a a* of the plate and tapered gradually back to 25 the plain surface of the upper part of the shi-

gle, as is shown by the edges *b b* of the raised point B.

C is the elongated elevated boss, formed, as shown, along the median line of the shingle.

D indicates the upper portion of the visible 30 face of the shingle. This is generally only outlined clearly when coupled with other similar shingles, and therefore forms no part of my design. The dotted lines indicate flanges, edges, &c., of the shingle, which are situated 35 outside of its visible face, and may be of any construction without in any way affecting my design.

I claim—

The design for a metallic shingle or roofing-plate herein shown and described, the same consisting of a shingle having a thickened lower edge, parallel sides *a a*, and the elevated elongated projection C, extending along the median line of its upper surface.

JACOB S. THORN.
